Primary Examiner — John Windmuller*Assistant Examiner* — Steven Czyz(74) *Attorney, Agent, or Firm* — Loginov & Associates, PLLC; William A. Loginov(57) **CLAIM**

The ornamental design for a wine carrier, as shown and described.

DESCRIPTION

FIG. 1 is a perspective view of a wine carrier;

FIG. 2 is a front view of the wine carrier;

FIG. 3 is a rear view of the wine carrier;

FIG. 4 is a right side view of the wine carrier;

FIG. 5 is a left side view of the wine carrier;

FIG. 6 is a top view of the wine carrier; and,

FIG. 7 is a bottom view of the wine carrier.

The broken line elements in all views are for illustrative and environmental purposes only and form no part of the claimed design.

1 Claim, 3 Drawing Sheets(56)
